UNITED STATES PATENT OFFICE.

HENRY TRENCHAM, OF RUISLIP, HERBERT C. HEATH, OF WEMBLEY, AND CALEB W. NEWTON, OF HARLESDEN, LONDON, ENGLAND, ASSIGNEES TO GENERAL ELECTRIC COMPANY, A CORPORATION OF NEW YORK.

ELECTRIC SWITCH.

Application filed September 8, 1925, Serial No. 55,188, and in Great Britain September 30, 1924.

Our invention relates to electric switches, particularly to switches of the type known as "iron-clad" wherein a number of units may be arranged side by side, each unit comprising a circuit breaker, usually an oil circuit breaker, one or more bus bar chambers, one or more feeder chambers, and one or more isolating devices or switches for each circuit.

One object of our invention is the provision of improved means for causing the terminals of the breaker properly to engage and be disengaged from the terminals of the desired bus bar and feeder chambers. Another object of our invention is the provision of improved means for automatically covering and uncovering the terminal of the bus bar and feeder chambers in accordance with the position of the breaker.

Our invention will be better understood from the following description taken in connection with the accompanying drawing, and its scope will be pointed out in the appended claims.

In the drawing, Figure 1 is a side view of a switch involving our invention, Figure 2 is an end view of the same and Figures 3 and 4 are details.

According to the arrangement illustrated, the switch consists of a frame 11 arranged at the top of which are three parallel chambers 12, 13 and 14, the center one 13 carrying the feeder terminals and the two outside chambers 12 and 14 carrying bus bars 15 and 16 with their respective terminals. These terminals are preferably socket terminals, there being three for each chamber, i. e., one for each phase. The three phase circuit breaker 17 is mounted on a horizontal structure 18, preferably a track, along which it is adapted to move, rollers 19 being provided whereby it can be supported. The supporting structure 18 may be lifted or lowered through the agency of a number of nuts 21 fixed to it, preferably at its four corners, operating with an equal number of vertically-arranged lifting screws 22, which screws may be geared together in any suitable way, as for example by means of a chain 23 and bevel gearing 24 so that upon operation of a handle or handles 25 all the screws revolve in the same direction at the same rate to raise or lower the structure uniformly, whilst keeping it in a horizontal plane. When in its operative lower position as indicated by the dot

and dash lines 20, the main outside terminals 55 of the circuit breaker, which are of the plug type and carried by the bushings 26, are withdrawn from the corresponding socket terminals in the feeder 13 and whichever bus bar chamber was previously connected. In 60 this position the circuit breaker can be moved horizontally on its track 18 to adopt a position from which when raised sufficiently it will interconnect the feeder chamber 13 with the other bus bar chamber through its external plug contacts. The plug contacts on the circuit breaker and the socket contacts in the bus bar and feeder chambers, it should be noted, constitute isolating devices. With this arrangement, it will be readily understood that horizontal movement of the circuit breaker is prevented except when the same has been lowered a predetermined amount in order that its plug contacts may be clear of the cooperating socket contacts.

Gravity-controlled shutters 27, 28 and 29 are shown arranged to close the lower ends of the bus bar and feeder chambers when the circuit breaker structure is lowered sufficiently, and any suitable operating mechanism 80 therefor may be provided whereby, when the circuit breaker is raised in order to close the isolating contacts in the circuit of the feeder chamber and one of the bus bar chambers, only the shutters covering these two chambers 85 will be operated to uncover them.

In order to ensure that, when the circuit breaker is raised to close these isolating contacts, it is in its correct horizontal position, a number of dowel pins cooperating with suitable guideways are arranged to guide the same during its upward movement or to prevent the upward movement thereof when the same is not in correct alignment. In the arrangement illustrated, the dowel pins 31 are 90 secured to the circuit breaker by brackets 32, pointing upwards in the vertical plane through the middle thereof, and are arranged, when the breaker is in its correct horizontal position, to pass between pairs of co-operating rollers 33 arranged, respectively, in the vertical planes between the feeder chamber and the bus bar chambers.

The dowel pins are arranged to operate the shutter-operating mechanism aforesaid, such 105 mechanism comprising rods 34 connected to the feeder chamber shutter 28 above and on each side of the pivot 35 thereof and also to

rocking levers 36 pivoted at 37. The ends of these levers normally lie just above the pairs of rollers 33, respectively, and are adapted to be engaged, respectively, by the dowel pin 5 upon the upward movement thereof according as to which of the extreme horizontal positions is occupied by the circuit breaker. With this arrangement when the circuit breaker is in a position, say, from which the 10 front bus bar chamber 12 can be connected to the feeder chamber 13, as illustrated, upward movement of the breaker operates the shutter mechanism to rotate shutter 28 up between the feeder chamber 13 and the back bus bar chamber 14. The shutter 28 is shown connected to the bus bar chamber shutters 27 and 29 by means of pins 38 working in slots 39 in the connecting rods 41 in such a way that shutter 27 is directly operated while the pin rides idly in 15 the slot of the connecting rod of the back bus bar chamber shutter 29 without operating it. In a similar manner, when the breaker is in a position from which the back bus bar chamber 14 may be interconnected with the feeder 20 chamber 13, upward movement of the breaker effects the rotation of the feeder chamber shutter 28 in the opposite direction i. e., between feeder chamber and the front bus bar chamber 12, operates the shutter 29 of the 25 back bus bar chamber directly, while the pin runs idly in the slot of the connecting rod of shutter 27 without operating the same. For mechanical reasons, similar shutter-operating mechanisms are preferably arranged on 30 each side of the structure.

Any suitable arrangement may be provided whereby the circuit breaker platform 18 cannot be lowered when it is in its raised position with the circuit breaker remaining closed. 40 For instance, movement of the handle 25 which operates the lifting and lowering gear of the platform 18 may be arranged to effect the tripping of the circuit breaker and to prevent the reclosing thereof, except when the 45 platform is lowered, in which position it may be desirable for testing or other reasons, to open and close the circuit breaker. When lowered it will readily be understood that the 50 feeder circuit is not connected with either of the bus bar circuits due to the fact that the isolating devices are fully open.

A suitable construction of interlock for this purpose is illustrated in Fig. 3, comprising a notched cam 42 pivoted at 43 to the breaker. 55 The sliding lever 44 is connected to the cam and the spring 45 biases the cam outwardly, in which position the inner end of the lever is just clear of the tripping bridge of the tripping mechanism 46. As shown in Fig. 3 the 60 circuit breaker is fully raised and the cam is in its outward position, the breaker thus being free to be closed or opened. When the movable structure 18 begins to be lowered, the lower side 47 of the cam, riding upon the 65 horizontal shaft 48 of the lowering and lift-

ing gear, forces the cam and sliding lever 44 inwardly, thus tripping the breaker before it has been appreciably lowered. The cam is so designed that the upper inclined portion 49 lies just below the shaft 48 when the breaker 70 is lowered sufficiently for the isolating devices to be opened in which position the breaker may be opened or closed. Thus, when the movable platform is raised, the inclined surface 49 rides against the shaft 48 and trips 75 the breaker, while the isolating device is still open, if the breaker were closed.

As it is sometimes desirable to ground the feeder circuit, improved means are provided for effecting this, in accordance with another 80 feature of our invention. This means comprises the extensions 50 which are adapted to be applied to the bushings 26 of the breaker and which engage with the isolating sockets of the fixed chambers when the breaker is 85 raised. Those extensions 50 which engage with the feeder sockets have conducting portions therein which connect the breaker with the feeder. Those extensions on the other bushings of the breaker have conducting portions which do not connect with the bus bars when the breaker is raised, being insulation covered, but instead each has a connection to ground. With the extensions 50 therefore properly placed the breaker when in the 90 raised position may be used for the purpose of opening and closing a ground connection to the feeder. When the breaker is fully raised, it will not be so high as in normal circumstances, due to the extensions 50, and the 95 notch 51 is provided in the tripping cam to permit the opening or closing of the breaker when in its "grounding" raised position. When the breaker is closed the feeder circuit is, of course, grounded.

Advantages of an arrangement according to our invention, as previously described, are a positive interlock whereby a feeder circuit can only be connected to one of the bus bar circuits at any given moment combined with certain means of indicating which bus bar is in use (i. e., the horizontal position of the breaker); considerable ease in changing over from one bus bar to another; security against coming in contact with the live terminal in 110 the bus bar chambers; and economy of space as compared with the truck type of switch gear. Another advantage resides in the fact that, when the breaker requires examination or cleaning, the breaker may be lowered until 115 its tank (or tanks) touches the ground or other support, the tank may then be detached, and the remaining parts of the breaker, leaving the tank, raised clear of the tank, no lifting gear being employed other than that which forms a part of the switch gear itself. Wheels may be provided on the lower end of the tank to allow of its easy removal.

What we claim as new and desire to secure by Letters Patent of the United States is:

1. An electric switch comprising a plurality of bus bar terminals and an intermediate feeder terminal, a circuit breaker having terminals thereon and means for moving the circuit breaker bodily to cause its terminals to engage either the feeder terminal and one bus bar terminal or the feeder terminal and the other bus bar terminal.
2. An electric switch comprising downwardly facing bus bar and feeder terminals, a circuit breaker having terminals adapted to engage said terminals, a track on which the circuit breaker is adapted to be moved horizontally and means for raising the track and the circuit breaker to cause the terminals of the breaker to engage the bus bar and feeder terminals.
3. An electric switch comprising a plurality of downwardly facing bus bar terminals and an intermediate feeder terminal, a track, a circuit breaker mounted to be moved horizontally thereon and having terminals and means for raising and lowering the track with the breaker whereby the breaker terminals may be brought into engagement either with the feeder terminal and one bus bar terminal or with the feeder terminal and the other bus bar terminal.
4. An electric switch comprising a plurality of uniformly spaced stationary terminals, a movable circuit breaker having a pair of fixed terminals, means for moving the breaker to selectively bring its terminals into engagement with different pairs of the stationary terminals, a shutter for each of the stationary terminals, and means responsive to movement of the circuit breaker toward a selected pair of stationary terminals for moving only the shutters of the selected pair of terminals.
5. An electric switch comprising a pair of bus bar terminals and a feeder terminal, a movable shutter for each terminal adapted in one position to cover its terminal, a circuit breaker having a pair of terminals and movable to a plurality of terminal connecting positions whereby in one position its terminals engage respectively the feeder terminal and one bus bar terminal and in another position engage the feeder terminal and the other bus bar terminal, and means responsive to the movement of the circuit breaker to one or the other of said positions for moving the shutters of the corresponding terminals to uncovering position, the remaining shutter being maintained in terminal covering position.
6. An electric switch comprising a plurality of stationary terminals, a movable circuit breaker having terminals adapted to engage the stationary terminals, an attachment for the circuit breaker forming extensions of its terminals, certain of said extensions being insulation covered and connected together and a ground connection for said insulated extensions.
7. A metal clad selective electric switching equipment comprising a plurality of stationary terminals arranged in alinement, a circuit breaker having terminals thereon adapted selectively to engage certain ones of the stationary terminals, a track on which the circuit breaker may be moved to bring it opposite the selected stationary terminals and means for moving the circuit breaker relative to the stationary terminals to cause engagement of the circuit breaker terminals with the selected stationary terminals.
8. A metal clad selective electric switching equipment comprising a plurality of downwardly facing stationary terminals arranged in horizontal alinement, a circuit breaker having a pair of terminals adapted to engage various selected pairs of said stationary terminals, a track on which the circuit breaker is adapted to be moved horizontally and means for raising the circuit breaker to cause its terminals to engage the selected pairs of the stationary terminals.
9. An electric switch comprising a plurality of bus bar terminals and a feeder terminal, a circuit breaker having cooperating terminals thereon and means for moving the circuit breaker relative to the bus bar and feeder terminals whereby the circuit breaker terminals selectively engage the feeder terminal and one bus bar terminal or the feeder terminal and the other bus bar terminal.
10. A metal clad electric switching equipment comprising a plurality of spaced stationary terminals, a circuit breaker movable in directions at right angles to each other and having terminals arranged selectively to be brought into conductive relation with pairs of said stationary terminals, shutter means for covering the stationary terminals, and means responsive to movement of the circuit breaker toward a selected pair of stationary terminals for actuating the shutter means to uncover the selected pair of stationary terminals only.
11. A selective electric switching equipment comprising a housing having therein a plurality of stationary terminals arranged to form two pairs of equally spaced terminals, a circuit breaker having a pair of similarly spaced terminals and having a plurality of operating positions in the housing, and means for movably mounting the circuit breaker in the housing, said breaker being adapted in one position to have its terminals connect with the stationary terminals forming one of said pairs and in another position to have its terminals connect with the stationary terminals forming the other of said pairs.

In witness whereof we have hereunto set our hands this 13th day of August, 1925.
